DISPLAY RACK FOR BOLTS OF FABRIC
OR THE LIKE

Nick Grande, Bronxville, N.Y., assignor to Loomskill, Inc., New York, N.Y.

Filed July 26, 1961, Ser. No. 66,079

Term of patent 14 years

(Cl. D80—9)

FIG. 1 is a front perspective view taken from one side of a display rack for bolts of fabric or the like embodying my new design, the rear being substantially the same;

FIG. 2 is an elevational view thereof taken from the side shown in FIG. 1, the opposite side being essentially the same; and

FIG. 3 is an enlarged fragmentary perspective view of one top corner thereof.

The broken line representations of bolts of fabrics in FIGS. 1 and 2 are for illustrative purposes only.

I claim:
The ornamental design for a display rack for bolts of fabric or the like, as shown and described.
